UNITED STATES PATENT OFFICE.

CHARLES D. TISDALE, OF EAST BOSTON, ASSIGNOR TO HIMSELF AND
BARNA W. TISDALE, OF BOSTON, MASSACHUSETTS.

IMPROVEMENT IN CAR-COUPINGS.

Specification forming part of Letters Patent No. 38,792, dated June 2, 1863.

To all whom it may concern:

Be it known that I, CHARLES D. TISDALE, of East Boston, in the county of Suffolk and State of Massachusetts, have invented an Improved Railway-Carriage Coupling; and I do hereby declare the same to be fully described in the following specification and represented in the accompanying drawings, of which—

Figure 1 is a side elevation, Fig. 2 a longitudinal and vertical section, and Fig. 3 a longitudinal and horizontal section, of it.

The nature of my invention consists in the combination of an intermediate elastic link pad with the connection link and the bunter, the said pad being affixed to the link.

The coupling in question is a "self-acting" one—that is, one which will connect two carriages by and during the process of bringing them together, so that the coupling-link of one may enter a bunter of the other of them.

In the drawings, A A exhibit the two bunters of the two cars or carriages, while B is their link, which, when the carriages are in connection, is coupled to the bunters by two pins, C C, which go vertically through such bunters, and also through the link, there being one of such pins to each bunter. A slider or auxiliary bunter, D, is arranged within the socket a of each bunter and in front of a spring, b, which is also placed within such socket. Each bunter-socket is provided with a conical mouth, c, the front end of each bunter-socket being made with a concavity. A pin-passage, d, is made down through the bunter A for reception of a pin, C. The link has the form shown in Fig. 3, or, in other words, is open, except in having a bearing, e, extended across its middle part. This plate serves as a rest or abutment to give support to an elastic cushion, E, through which the link passes, and which is interposed between the two bunters A A when their carriages are in connection. The link-cushion, being affixed

to the link, serves, by bearing against the bunter head or end, to maintain the link in or about in a horizontal position preparatory to the operation of coupling two carriages. It also permits the link to swing or swerve laterally more or less on its pins, and subsequently operates to restore the link to its normal position. It also answers the purpose of a spring or fender to relieve the shock of contact of the two bunters. By raising the pin of either bunter so as to disengage it from the other the auxiliary bunter within that bunter containing the raised pin will be shot forward by its spring, and will project by or across the pin-passage in such manner as to hold up the pin or prevent its descent. By bringing the primary bunters together so as to force the link into that one from which it may be disconnected the projecting end of the link will be forced against the free auxiliary bunter, and so as to press it backward and relieve the pin, which, by its gravitating power, will be caused to fall down into the link, and thereby couple the bunters together.

I am aware that it is not new, and, consequently, do not claim, to combine with a bunter a device not only for supporting the link-pin when raised therein, but capable of being moved from underneath such pin by the link in the process of forcing the link into the bunter, the same being so as to set free the pin, in order that it may be caused by gravity to fall down through the link, and thereby couple the two bunters together.

What I claim, however, is—

The combination of the intermediate elastic cushion or link-pad, E, with the link B and the bunter A, the said link-pad being affixed to the link, and so as to operate as specified.

C. D. TISDALE.
